(57) **CLAIM**

The ornamental design for an ergonomic hand grip, as shown and described.

DESCRIPTION

FIG. 1 is a perspective view, looking from the top, of an ergonomic hand grip showing our new design;

FIG. 2 is a top plan view thereof;

FIG. 3 is a bottom plan view thereof;

FIG. 4 is a first side elevational view thereof, the opposite side elevational view being a mirror image thereof;

FIG. 5 is a first end elevational view thereof; and,

FIG. 6 is the opposite end elevational view thereof.
